Primary Examiner — Rhea Shields(74) *Attorney, Agent, or Firm* — Law Offices of Albert
Wai-Kit Chan, PLLC(57) **CLAIM**

The ornamental design for a medical trolley, as shown and described.

DESCRIPTION

FIG. 1 is a front, right-side, top perspective view of a medical trolley showing our new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The equal length broken lines in the drawings depict portions of the medical trolley that form no part of the claimed design.

1 Claim, 7 Drawing Sheets(56)
